US0D1026106S

(12) **United States Design Patent** (10) **Patent No.:** **US D1,026,106 S**
(45) **Date of Patent:** **** May 7, 2024**

(54) **PERSONAL TRANSPORT VEHICLE**

(71) Applicant: **NantMobility, LLC**, Culver City, CA (US)

(72) Inventors: **Patrick Soon-Shiong**, Los Angeles, CA (US); **Thomas M. Wittenschlaeger**, Flowery Branch, GA (US); **Nathan H. Allen**, Pasadena, CA (US)

(73) Assignee: **NantMobility, LLC**, Culver City, CA (US)

(**) Term: **15 Years**

(21) Appl. No.: **29/896,295**

(22) Filed: **Jun. 30, 2023**

Related U.S. Application Data

(63) Continuation of application No. 29/862,428, filed on Dec. 8, 2022, now Pat. No. Des. 996,527, which is a continuation of application No. 29/837,502, filed on May 5, 2022, now Pat. No. Des. 978,256, which is a continuation of application No. 29/750,478, filed on Sep. 14, 2020, now Pat. No. Des. 951,361.

(57) **CLAIM**

The ornamental design for a personal transport vehicle, as shown and described.

DESCRIPTION

FIG. 1 is an isometric view of a personal transport vehicle in accordance with our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown are included for the purpose of illustrating portions of the personal transport vehicle which form no part of the claimed design.

1 Claim, 7 Drawing Sheets
